DESIGN FOR A SHUTTLE CASE BEARING

Samuel A. Bethune, United States Army, and
Emmett G. Comstock, Prince George County,
Va.

Application March 26, 1942, Serial No. 106,330

Term of patent 3½ years

To all whom it may concern:

Be it known that we, Samuel A. Bethune, United States Army, and Emmett G. Comstock, an employee of the Government, citizens of the United States, residents of Prince George County, Virginia, have invented a new, original, and ornamental Design for a Shuttle Case Bearing, of which the following is a specification, reference being had to the accompanying drawing, forming part thereof.

Fig. 1 is a front elevational view of a shuttle case bearing showing our new design,
Fig. 2 is a rear elevational view, and
Fig. 3 is a bottom plan view thereof.

We claim:
The ornamental design for a shuttle case bearing, as shown.

SAMUEL A. BETHUNE.
EMMETT G. COMSTOCK.
